UNITED STATES PATENT OFFICE.

WILLIAM FRIEDMAN, OF JEFFERSON BARRACKS, MISSOURI.

COMBINATION TOILET ARTICLE.

Application filed February 7, 1925. Serial No. 7,554.

To all whom it may concern:

Be it known that I, WILLIAM FRIEDMAN, a citizen of the United States, residing at Jefferson Barracks, in the State of Missouri, have invented a Combination Toilet Article, of which the following is a full and complete specification.

My invention is an improvement in toilet articles and relates more especially to that particular class in which several articles of this character are combined for the purpose of economizing space.

The primary object of my invention is to provide a combination toilet article to include a brush, comb and small looking-glass in compact arrangement and particularly adapted for the use and convenience of those engaged in camping, field work, &c., whereby the comb and looking-glass combined with the brush will not only economize space in packing them into a kit or luggage-carrier but the several articles can be conveniently handled when in use.

A further object of my invention is to so combine the comb in connection with the brush that it will be housed in the handle of said brush and hinged to swing outwardly therefrom into fixed position alongside of one edge thereof for use in combing, the arrangement facilitating the manipulation of the comb by gripping the handle of the brush and the particular means of attachment in the present instance providing for easily detaching the comb for substituting another having teeth more or less closer together, applying a new comb in place of one that is broken and for separating the articles in cleaning the same.

Other objects and advantages of my invention will hereinafter appear, and what I claim as new and desire to protect by Letters-Patent is more specifically set forth in the appended claims.

In the accompanying drawings:—

Figure 1 is a side elevation of a combination toilet article constructed in accordance with my invention.

Fig. 2 is a bottom plan view of the same.

Fig. 3 is a bottom plan view with the handle of the brush and part of the back thereof in section to show the recesses which receive the comb and looking-glass.

Fig. 4 is a sectional view on the line 4—4 of Fig. 3, and

Fig. 5 is a sectional view on the line 5—5 of Fig. 3.

In carrying out my invention the handle and back of the brush, formed in one piece, are recessed so that the other toilet articles—comb and looking-glass—may be completely housed therein and the comb firmly connected to the brush when it is swung into position for use, the handle 10 being provided with a recess 11 extending nearly its full length and opening out at one edge thereof to receive the comb 12, while the body portion or back 13 of the brush is provided with a shallow recess 14 extending inwardly from the outer end thereof to receive the looking-glass 15, and with a longitudinal recess 16 in one edge thereof in which the comb is held, as hereinafter described, when in position for use. By reference to Fig. 4 it will be seen that the recess 11 is shaped in cross-section to correspond with a comb of conventional form; that is tapered from back to outer end of the teeth; and of course the length of said recess also corresponds approximately with the length of the comb, being extended at its outer end so as to not interfere with the swinging movement of said comb in and out of the recess. The longitudinal recess 16 along one edge of the back of the brush joins the recess 11 in the handle and at the juncture of these recesses there is pivoted, on pin 17 a metal hinge 18 of U-shape construction (see Fig. 5) to receive one end of the back of the comb 12 for hinging said comb to the brush so that it may be swung from one of the recesses to the other. The side members of the U-shaped hinge 18 are curved inwardly, as shown, to engage in the grooves 12^a usually formed in the sides of the back of a comb, and as said hinge is preferably made of spring metal the side members will firmly grip the comb when it is inserted therein. To receive this hinge the recess 16 is slightly enlarged, as shown, the other part of said recess being of approximately the same width as the back of the comb so that it will fit snugly therein while the depth provides the required bearing to prevent lateral movement of the comb when in use.

The comb 12 is of a conventional shape having the longitudinal grooves 12^a in the opposite sides thereof, as hereinbefore explained, and when connected to the hinge 18 by engaging an end portion therewith said comb may be swung into the recess 11 of the brush and housed therein when not in use and also swung to seat in the recess

16, in which latter position the teeth project outwardly from the brush for using said comb. To firmly secure the comb in recess 16 there is a spring metal clip 19 at the outer end of said recess which engages a recess 20 in the end of the comb, and in like manner the comb is held securely housed in the recess 11 by a metal clip 21, but in this latter instance the clip presents side members 21^a 21^a between which the comb is clamped, and to more securely hold it housed in said recess the side members are slightly curved inward, as shown in Fig. 4, to engage in the grooves 12^a. To receive this clip 21 the outer end of the recess 11 is enlarged, at 11^a, and the side members of said clip are normally separated so that the outer ends of the teeth of the comb will pass between the same and wedge them apart for engagement with the back of said comb in the grooves 12^a as aforesaid. It will be noted, also, that the curved portion of the spring metal clip 19 in the outer end of recess 16 yields for movement of the comb into said recess and for engagement with the recess or notch 20.

The looking-glass 15 is of the ordinary plain type employed in connection with toilet cases, etc., and having a tab 15^a for convenience in withdrawing it from the recess in the back of the brush.

The utility of the combination toilet article hereinbefore described will be readily apparent, for in order that the brush may hold the other essential articles—comb and looking-glass—it is necessary only to make the handle of the brush a little wider than usual without affecting the grip of the hand in its manipulation, and of course the width of said handle depends upon the size of the comb used. When the comb and looking-glass are housed in the brush it provides a combination article that will reduce the amount of space required in packing the articles separately in a kit or luggage-carrier, thereby adapting it especially for the use of those engaged in camping out, on field work, or in other situations where it is desired to economize space in carrying these articles or have it more convenient in handling the same for other purposes.

In using the article after removing the glass the comb is swung from its housing to the position at the edge of the brush, and then one's hair may be brushed and combed by manipulation of the brush for either purpose, the comb not interfering with the operation of brushing, and vice versa.

I claim:—

60 1. A combination toilet article comprising a brush having a recess in its handle to receive a comb, a comb hinged to the brush so as to be housed in said recess and movable to positions alongside one edge of the back of the brush, said comb having a notch in

its outer end, and a spring clip attached to the brush to engage the aforesaid notch in the comb when the latter is in the position at one edge of the back of the brush.

2. A combination toilet article comprising a brush having a recess in its handle to receive a comb and a recess in an edge of the back of said brush to receive the back of the comb, and a comb pivoted between the aforesaid recesses for movement from one to the other. 70

3. A combination toilet article comprising a brush having a recess in its handle to receive a comb and a recess in an edge of the back of said brush to receive the back of the comb, a hinge pivoted at the intersection of the aforesaid recesses, and a comb attached to the hinge whereby said comb may be swung into the recess in the handle to be housed therein and into the recess in the edge of the back of the comb in position for use. 80

4. A combination toilet article comprising a brush having a recess in its handle to receive a comb and a recess in an edge of the back of the brush to receive the back of the comb, a hinge pivoted between the aforesaid recesses, a comb attached to the hinge for swinging movement into the handle and into engagement with the recess in the back of the brush, and means carried by the brush to engage the comb in either the aforesaid positions. 90

5. A combination toilet article comprising a brush having a recess in its handle to receive a comb and a recess in an edge of the back of the brush to receive the back of the comb, a comb pivoted between the aforesaid recesses for swinging movement into the handle and into engagement with the recess in the back of the brush, and means carried by the brush to engage the comb in either the aforesaid positions. 100

6. A combination toilet article comprising a brush having a recess in its handle to receive a comb and a recess in an edge of the back of the brush to receive the back of the comb, a U-shaped hinge pivoted between the aforesaid recesses, and a comb engaging the U-shaped hinge for swinging movement 110 with respect to the aforesaid recesses. 105

7. A combination toilet article comprising a brush having a recess in its handle opening out at one edge thereof to receive a comb and a recess in an edge of the back of the brush to receive the back of the comb, a U-shaped hinge pivoted between the aforesaid recesses and having inwardly curved side members, and a comb engaged between said side members and having grooves receiving the latter. 120

8. A combination toilet article comprising a brush having a recess in its handle opening out at one edge thereof to receive a comb and a recess in the edge of the back of 130

the brush on a line with the open end of the aforesaid recess to receive the back of the comb, a U-shaped hinge pivoted between the aforesaid recesses and having inwardly 5 curved side members, a comb engaged between said side members and having grooves receiving the latter, a clip in the outer end of the recess in the back of the brush to engage the outer end of the comb, and a clip in 10 the outer end of the recess in the handle of the brush to engage the comb when it is housed in said recess.

9. A combination toilet article comprising a brush having a recess in its handle

opening out at one edge thereof to receive a 15 comb, a recess in the edge of the back of the brush on a line with the outer end of the aforesaid recess to receive the back of the comb, and a recess in the body of the brush to receive a looking-glass, a U-shaped hinge 20 pivoted to the brush between the recesses in the handle and edge of the brush, a comb attached to the hinge to swing into the adjoining recesses, and clips attached to the brush and engaging the comb to hold it in 25 the recesses in either position of said comb.

WILLIAM FRIEDMAN.
